UNITED STATES PATENT OFFICE

155,427

DESIGN FOR A TROLLING SINKER

Karl M. Ingalls, Texas City, Tex.

Application November 8, 1948, Serial No. 149,526

Term of patent 7 years

(Cl. D31—4)

To all whom it may concern:

Be it known that I, Karl M. Ingalls, a citizen of the United States, residing at Texas City, in the county of Galveston and State of Texas, have invented a new, original, and ornamental Design for a Trolling Sinker, of which the following is a specification, reference being had to the accompanying drawing, forming part thereof.

Figure 1 is a top plan view of a trolling sinker, showing my new design;

Figure 2 is a side elevational view thereof;

Figure 3 is a front elevational view, and

Figure 4 is a rear elevational view of the same.

I claim:

The ornamental design for a trolling sinker, as shown.

KARL M. INGALLS.
